UNITED STATES PATENT OFFICE.

CHARLES J. A. MACHUT, OF SHEBOYGAN FALLS, WISCONSIN.

SAFETY DEVICE.

No. 798,687.

Specification of Letters Patent.

Patented Sept. 5, 1905.

Application filed January 11, 1905. Serial No. 240,541.

To all whom it may concern:

Be it known that I, CHARLES J. A. MACHUT, a citizen of the United States, and a resident of Sheboygan Falls, in the county of Sheboygan and State of Wisconsin, have invented certain new and useful Improvements in Safety Devices; and I do hereby declare that the following is a full, clear, and exact description thereof.

10 My invention relates to safety devices for use in factories and other places fitted with lines of shafting; and it consists in certain peculiarities of construction and combination of parts, as will be fully set forth hereinafter in connection with the accompanying drawing and subsequently claimed.

In the said drawing the figure represents a line of shafting with my improved safety device arranged adjacent thereto.

20 Referring by numerals to the said drawing, 1 designates a line of shafting on which there is loosely mounted a belt-pulley 2.

25 4 designates a spider-frame having a hub fast on the shaft 1, the arms of this spider having ears 5, to which are centrally pivoted levers 6, to whose outer ends are secured bolts 7 for engagement with holes in the spider-arms and web of the pulley 2.

30 8 designates a hub sliding on the shaft 1 and guided by feather 9 thereon. This hub has ears 10, to which are pivoted the adjacent ends of links 11, whose other ends are pivoted to the inner ends of the hereinbefore-named levers 6. Hence when the hub 8 is moved toward the pulley 2 the bolts 7 are withdrawn from the holes in the pulley-web, and said pulley is thereby loose on the shaft 1; but if the hub 8 is moved away from the said pulley this will force the said bolts 7 into said holes, there-40 by causing the said device to act as a clutch.

35 12 represents a lever, which is attached by pivot-bolt 13 to some convenient part of the structure containing the shafting (and is preferably made like a spanner) at some little dis-45 tance from its pivotal point, as shown at 14 14. The hub 8 is formed with an annular exterior groove near its outer end in which is fitted a loose ring 15, from which there project pins 16, which engage with holes in the 50 spanner parts 14 of the lever 12, whereby the hub 8 is permitted to revolve with the shaft 1 and be capable of being moved longitudinally on said shaft by said lever 12.

17 designates a friction-pulley fast on the

shaft 1, which pulley ordinarily runs free 55 therewith; but suspended by a loop 18 from any convenient adjacent part of the structure is a strap 19, preferably of metal, surrounding said pulley 17, the ends of said strap being connected together and to an upright 20 60 by the head of a lever 21, pivoted to said upright, so that a downward pull on said lever will serve to draw the ends of the strap together and bind the strap on the pulley, forming a friction-brake. 65

22 represents a weight-well, within which travels a weight 23, having a ring 24 secured at its top, to which a cord 25, ending in spring 26 from the lever 21, is connected. Another cord 27 extends from the ring 24 to and 70 around a windlass-roller 28, supported above the weight-well, this cord being wound up by a crank 29 and the said roller having a lateral pin 30, which when the weight has been wound up to the top of the weight-well, normally rests on a lever 31 to keep the roller from being turned by the weight. This lever is pivoted by pivot-bolt 32 at one end to an adjacent part of the structure to which is also secured a guide or keeper 33 to limit the 75 movement of the free end of said lever.

Parallel with the line of shafting 1 is a line of wire, cord, or other cable (indicated at 34 34) made in sections and united by series of bell-crank levers 35 35 35, secured to the 85 structure (not shown) and preferably connected together, and from one of these bell-cranks a cord 36 extends to the hereinbefore-named lever 31.

The weight-well 22 is formed with a vertical slot 37 in one of its walls, through which there projects one end of a lever 38, whose other end is secured by pivot-bolt 39 to any convenient part of the structure, (not shown,) which structure also supports small sheaves 95 40 and 41, and a cord 42 extends from the lever 38 up and around the said sheaves 40 41 and to the free end of the hereinbefore-named lever 12, the end of the lever 38, which projects into the weight-well 22, being under and 100 in the path of the raised weight 23.

The object of my invention is to afford means for the quick stoppage of the revolution of the shafting 1 in the event of any one becoming caught or entangled thereby, and 105 the operation of my device will be readily understood from the foregoing description of its construction, taken in connection with

the accompanying drawing. As already explained, the wire, cord, or other cable 34 follows the line of shafting 1 at a slight distance therefrom, this being made possible by 5 the described bell-crank levers 35, so that counter-shafts may be followed by the parallel cable 34 all over the building. Now, for example, if a workman gets entangled in any manner with the shafting his arm, leg, or 10 other part of the body will shortly come in contact with said cable 34 and this draws on the bell-crank levers, and as soon as the lever connected to cord 36 is drawn on this will pull on lever 32 and withdraw it from under 15 the detent-pin 30, whereupon the weight 23 will be free to descend, unwinding the cord 27 on the windlass-roller 28, and in such descent the weight will first strike the inwardly-projecting end of lever 38. This will instantly draw on cord 42, and thus on the free 20 end of lever 12, thereby forcing hub 8 in toward the belt-pulley 2, and thus through the described clutch-levers and connections withdrawing the bolts 7 from the web of said pulley 2, so that same will run free of the shaft 1. However, the momentum of the shaft would cause same to continue to revolve and injury to the workman might result therefrom; but as the weight 23 continues to descend in the weight-well 22 it will presently 25 draw on the cord and spring 25 26 and through these on the attached end of lever 21, thus drawing the strap 19 down tight on the friction-pulley 17, thus forming an effective friction-brake, which will instantly stop the revolution of the pulley 17, and thus of the shaft 1, to which it is rigidly attached, thus serving by stopping the shafting and all the parts 30 connected thereto or operated therefrom to save life and limb of the imperiled workman.

As before stated, I have not thought it advisable to obscure the drawing by showing a multitude of beams and rafters constituting the structure of the factory; but I have shown 45 the pivotal connections in each instance by which the various levers, sheaves, or other parts are attached to such structure, so that there would be no uncertainty in this respect by those skilled in the art, and where I have 50 referred to a cord, wire, or cable, it will be understood that any preferred flexible connection may be employed.

Having thus described my invention, what I claim as new, and desire to secure by Letters Patent, is—

1. The combination with a line of shafting having a power-pulley with clutch mechanism thereon, and a lever for operating the latter, of a safety device comprising a line of cable extending parallel to said line of shafting, 55 and made in sections, and bell-crank levers uniting said sections; a weight-well; a weight movable therein, a windlass-roller, and an adjacent pivoted lever supported above said weight-well; a cord extending from said weight to and around said roller; a detent-pin on said roller normally resting on said adjacent lever; a cord connecting said lever with one of the bell-crank levers of the said line of cable parallel to the line of shafting; a lever 60 projecting into the weight-well in the path of the descending weight; and a cord connecting said lever with the lever that operates the clutch mechanism on the line of shafting.

2. The combination with a line of shafting 75 having a power-pulley for operating the same, of a friction-pulley fast on said shafting; a strap surrounding said friction-pulley, the ends of said strap being connected together and to the head of a lever to form a friction-brake by the depression of the latter; a line of cable extending parallel to said line of shafting, and made in sections, and bell-crank levers uniting said sections; a weight-well; a weight movable therein; a windlass-roller, 80 and an adjacent pivoted lever supported above said weight-well; a cord extending from said weight to and around said roller; a detent-pin on said roller normally resting on said adjacent lever; a cord connecting said lever with 85 one of the bell-crank levers of the said line of cable parallel to the line of shafting; and a flexible connection between the said weight, and the lever connected to the said friction-strap.

In testimony that I claim the foregoing I have hereunto set my hand, at Sheboygan Falls, in the county of Sheboygan and State of Wisconsin, in the presence of two witnesses.

CHARLES J. A. MACHUT.
